UNITED STATES PATENT OFFICE.

JAMES MONTICELLI, OF KENOSHA, WISCONSIN.

MOVING-PICTURE AND SOUND-REPRODUCING MACHINE.

Application filed April 1, 1922. Serial No. 548,648.

This invention relates to a combined moving picture and sound reproducing machine, and the object is to provide an apparatus designed for taking pictures of a singer during the time the record is being made, these pictures being produced on a continuous film and reproduced subsequently on a moving picture machine mounted within the cabinet of a talking machine of commercial type, the phonographic record being simultaneously reproduced.

A further object is to provide suitable operating mechanism, whereby the timing of the various portions of the mechanism is effectively controlled.

A still further object is to provide for throwing out of operation either the picture making or the picture reproducing device.

With the foregoing and other objects in view, the invention consists in the novel construction and arrangement of elements described and claimed, it being understood that modifications may be made within the scope of the claims, without departing from the spirit of the invention.

In the drawings, Figure 1 is a vertical section through the cabinet which houses the operative mechanism illustrated chiefly in elevation; Figure 2 is a horizontal section through the upper portion of the cabinet, showing at the right the camera for taking pictures, the electric motor and shaft driven thereby, and showing the projecting machine at the left.

The cabinet of a sound reproducing machine of a standard commercial type, is designated 10, the cover being shown at 11, and the record mounting disk being designated 12.

This disk 12 is driven by shaft 13 carrying a bevel pinion 14 meshing with bevel pinion 15 on motor shaft 17. The tone arm is shown at 18, and the screen of fibrous material 20, is mounted in the position shown, and the sound vibrations pass through this screen, on which the pictures are also projected.

Carried by shaft 17, driven by the motor, is a gear wheel 22, and on shaft 23 is a 50 slideable gear 24 rotatable with shaft 23. This gear 24 is thrown into mesh by means of a pivoted arm 27 controlled by rod 28 and lever 29. Bevelled gears 30 and 31 drive shaft 32 from shaft 23, and similar gears 33 and 34 drive shaft 35 and film roll 36 of

camera 37. This camera is mounted on a bracket 38 carried by the wall of the cabinet. The film is designated 39, and the upper film roll is shown at 40. The driving mechanism just described is supported in bearings of bracket 42.

It is intended that this camera shall be employed for taking pictures of the artist, on a continuous film, at the time the original record is being produced by suitable receiving means, not illustrated.

The moving picture projecting machine is designated 45 and is mounted on a bracket 46 supported on the wall of the cabinet. The upper film roll is designated 47, and the lower film roll shown at 48. The latter being driven by means of shaft 49, bevel gearing 50, shaft 51, mounted in bearing 52, and gearing 53 driving from shaft 54. This shaft last named carries a slideable gear 55 wheel 55 rotating with the shaft and controlled by rod 56 and lever 57. A gear wheel 58 on shaft 59 is adapted to mesh with gear wheel 55 when desired, and shaft 59 carries a bevelled pinion 60 meshing with pinion before named. Shafts 23 and 54 may be termed intermediate shafts, in view of their position between driving shaft 17 and shafts 32 and 51 controlling the operative elements of the camera and projecting machine.

At the time the original record is made, pictures of the artist or performer are made on a continuous film by means of camera 37, the controlling lever 29 being first shifted to throw into mesh the operating means for the film of the camera. The pictures of the developed film are subsequently projected by machine 45, the operating mechanism therefor being thrown in by lever 57, the record being reproduced simultaneously, and the timing corresponding with the timing when the record and film were first reproduced.

The machine 45 is mounted at an angle and permits the pictures to be projected on the screen 20 through which the sound vibrations are emitted.

The apparatus for producing the original record is not shown in detail, but is illustrated conventionally and the speaker's horn 105 is designated 65.

What is claimed is:

The combination with a camera and projecting machine, of shafts for driving the operative elements of said camera and pro-

jecting machine, a driving shaft, a turn table and gearing between the table and driving shaft, intermediate shafts geared respectively to the shafts first named, means including a clutch and gearing for placing the other intermediate shaft in operative relation to the gearing between the table and driving shaft. In testimony whereof I affix my signature.

5 including a clutch and gearing for placing one of the intermediate shafts in operative relation to the driving shaft, and means in-

JAMES MONTICELLI.
